UNITED STATES PATENT OFFICE.

FREDERICK W. PENDERGAST, OF CAMBRIDGE, MASSACHUSETTS.

DIVING APPARATUS.

1,343,744.

Specification of Letters Patent. Patented June 15, 1920.

Application filed February 27, 1919. Serial No. 279,595.

To all whom it may concern:

Be it known that I, FREDERICK W. PENDERGAST, a citizen of the United States, residing at Cambridge, in the county of Middlesex 5 and State of Massachusetts, have invented new and useful Improvements in Diving Apparatus, of which the following is a specification.

This invention has for its object to provide a diving apparatus whereby an observer or observers may descend to the bottom of a body of water for the purpose of locating sunken vessels, etc., the apparatus being sufficiently buoyant to maintain it normally 10 at the surface, and provided with means whereby it may be submerged and maintained at or near the bottom, the submerged means when in operation overcoming the buoyancy of the apparatus and holding it down, and when inoperative, permitting the apparatus to rise to the surface, the apparatus being provided with means for propelling it horizontally, and for directing its horizontal movement.

25 My invention does not contemplate the provision of means for enabling an observer to leave the apparatus while it is submerged, the chief function of the apparatus being to enable an observer therein to locate sunken 30 vessels preparatory to raising them by other means.

The invention is embodied in the improvements which I will now proceed to describe and claim.

35 Of the accompanying drawings forming a part of this specification,—

Figure 1 is a vertical section of a diving apparatus embodying the invention.

Fig. 2 is a fragmentary view of a portion 40 of the structure shown by Fig. 1, the movable part or spindle, hereinafter referred to, being differently adjusted.

Fig. 3 is a side view showing the line, anchor, and float hereinafter referred to, as 45 they appear when in operation.

The same reference characters indicate the same parts in all of the figures.

50 My improved apparatus includes a strong metallic shell adapted to contain one or more observers and to resist external water pressure when submerged to a considerable depth. As here shown, the shell is composed of a cylindrical metal body 12, an upper head 13, and a lower head 14, these parts being 55 suitably connected to form a fluid-tight receptacle or chamber, the several openings

hereinafter described in the wall of the shell being closed against the admission of water. The wall 12 is provided with a sight opening 60 protected by a heavy externally convex glass lens 15. Two or more of these protected sight openings may be provided, the lens 15 being sufficiently thick and heavy to resist any water pressure to which it may be subjected.

65 16 represents a buoyant external float, formed as an annular jacket surrounding the upper portion of the cylindrical body of the shell and composed of cork or any other suitable material, the buoyant material being preferably incased for protecting it against abrasion, and the jacket being preferably confined between external flanges on the shell by metal hoops or bands 17. The float 16 is located above the center of 70 gravity of the shell and is so proportioned that it imparts sufficient buoyancy to the shell to normally maintain the latter at the surface of the water, with its longitudinal axis upright, so that the head 13 will always 75 be at the upper end and the submerging propeller hereinafter described at the lower end, said head being provided with a man-hole having a suitable cover 18 adapted to be released both from the interior and exterior 80 of the shell.

The wall 12 is preferably reinforced internally by annular metal bands 19, so that the shell is adapted to resist heavy external pressure.

90 20 represents a compressed air reservoir formed as a helical tube, the convolutions of which surround the passenger-containing space in the shell, so that provision is made for storing an ample volume of compressed 95 air, without encroaching objectionably on the space required by the observers. The reservoir 20 is provided with an outlet cock 21, to release air to the interior of the shell. Suitable means, not shown, should be provided for forcing vitiated air from the shell 100 into the surrounding water.

22 represents a longitudinal shaft extending through the lower end or head 14 of the shell, and provided with a submerging propeller 23 adapted, when rotated in one direction, to draw the chamber downward in a body of water to any desired depth. The shaft 20 may be driven by an electric motor 24.

110 25 represents a lateral shaft extending through one side of the shell between the

upper and lower ends thereof, and provided with a lateral propeller 26, adapted to impart a sidewise movement to the shell. The shaft 25 is driven by a motor 27 through any suitable driving connections, connecting the motor shaft 28 with the shaft 25. As here shown, said shafts are provided with sprocket wheels connected by a sprocket chain 29.

- 10 30 represents a tubular elbow-shaped or angular rudder-post having an inner horizontal portion journaled in a bearing in the wall of the shell, and an outer portion which stands at an angle to the journaled inner portion, and is provided at its outer end with an incandescent electric lamp 31, or with a plurality of such lamps inclosed in a heavy glass protector, preferably formed as a hollow sphere of glass and of sufficient thickness to withstand heavy water pressure. The lead wires connected with the filament of the lamp 31 are extended through the rudder-post 30 and connected with a source of electricity, such as a storage battery 33, which 25 may be also connected with the motors 24 and 27. The rudder-post 30 is adapted to be turned by an occupant of the shell, the inner end of the post being here shown as provided with a crank 34. An observer in 30 the shell is therefore enabled to swing the lamp through an arc of a circle, and thereby illuminate different portions of the water adjacent to the sight opening, the lamp being preferably normally arranged above 35 the sight opening, as shown by Fig. 1.

I utilize the rudder-post 30 to carry a rudder 35, which is caused, by swinging movements of the post, to direct the horizontal movements of the shell caused by the lateral 40 chamber 26.

The shell is provided with a floor 36, separated from the lower end or head 14 of the shell by a space which contains the motors and storage battery above referred to. The 45 lower end or head 14 is provided with an annular guard or protecting cage 37, surrounding the submerging propeller and open for the free movement of water in all directions. Said guard prevents the propeller from 50 striking the bottom or any object in the path of the shell during its descent.

39 represents a fixed hooked arm attached preferably to the lower end of the shell and projecting therefrom, said arm being so 55 formed that it may be caused, by imparting combined horizontal and vertical movements to the shell, to engage a cable, or other object, and move the same as may be desired.

An observer enters the shell while its upper end is above the surface of the water, the man-hole cover 18 being then closed. The submerging propeller 23 is then driven and submerges the shell to any desired depth. The observer looking through the sight openings is enabled to see any submerged vessel 65

that may be illuminated by the lamp. It is necessary to continuously rotate the submerging propeller to maintain the shell at the desired depth. When the operator desires to move the shell sidewise, the lateral propeller 26 is driven, and the rudder is used to direct the course. The operator is therefore enabled to move the shell about, so that its sight openings may face in any desired direction. He is also enabled to impart upward movement to the shell, by stopping the rotation of the submerging propeller, or by reversing such rotation. The arm 39 may be moved, therefore, under a submerged cable, and then moved upward 70 to engage the cable and move it to another position. When the rotation of the submerging propeller is stopped, the buoyancy of the shell causes it to rise to the surface. This movement may be accelerated, if desired, by reversing the rotation of the submerging propeller. When the shell is moving vertically, the lateral propeller is at rest.

To enable the location of a sunken vessel to be marked, I provide the shell with a coiled line 40, having at one end an anchor 41, and at the other end a float 42. The shell is provided with suitable means operable by an occupant for releasing the line and permitting the anchor to drop to the bottom, and the float to rise to the surface, as indicated by Fig. 3. The coil-confining and releasing means here shown, is embodied in a fixed elbow-shaped arm 43, and a horizontal rod 44, movable in an orifice in the 95 wall of the shell. When the rod is retracted, as shown by Fig. 2, the coil 40 is placed in position to receive the rod, the latter being then projected through the coil and against the outer end of the arm 43, as shown by 100 Fig. 1. The coil is thus secured to the shell and may be released by retracting the rod 44 against a suitable stop 45.

The openings in the wall of the shell through which the propeller shafts, the 110 light-carrying arm, and the rod 44 pass, are provided with suitable stuffing boxes to form water-tight joints around the said parts.

The construction of the shell may be such that it will withstand water pressure of four hundred and fifty pounds to the square inch, this being the pressure at a depth of one thousand feet. The shell may be adapted for use in taking submarine photographs, the sight openings being made considerably 115 larger than here shown. The shell may be provided with electric or other heating means.

It will be seen that the described apparatus is independent of hoisting means at 125 the surface and is self-submerging and self-raising.

I claim:

1. A dirigible diving apparatus comprising a fluid-tight shell composed of a cylind-

drical body and heads at opposite ends of the body, a tubular float surrounding one end portion of the body and arranged relatively to the center of gravity of the shell 5 to maintain the shell with its longitudinal axis vertical, so that one of said heads is at the upper end and the other head at the lower end, the upper head being provided with a man-hole, and with a cover therefor, 10 a vertical shaft journaled in a bearing in the lower head, and provided with a propeller adapted to move the shell vertically in either direction, a horizontal shaft journaled in a bearing in the body between the heads, 15 and provided with a propeller adapted to move the shell horizontally, and steering means composed of an angular rudder-post having an inner horizontal portion journaled in a bearing in the body adjacent to 20 the horizontal shaft bearing, and an outer portion at an angle to the inner portion, and a rudder attached to said outer portion, said steering means being adapted to change the course of the apparatus when it is moving 25 horizontally.

2. A diving apparatus substantially as specified by claim 1, the said rudder-post being tubular and provided at its outer end with an electric lamp, the tubular post serving as a conduit for conducting wires. 30

3. A diving apparatus comprising a passenger-containing fluid-tight shell having means whereby it may be moved vertically in a body of water, the shell being provided at its exterior with bottom-marking means, 35 composed of a buoy, an anchor and a coiled line connecting the float with the anchor, and with means for releasably securing the line to the shell, said means being operable by an occupant of the shell to detach 40 the line and permit the buoy to rise to the surface, and the anchor to drop to the bottom.

In testimony whereof I have affixed my signature.

FREDERICK W. ^{his} X PENDERGAST.
